(57) **CLAIM**

The ornamental design for a low-profile aquarium light with ventilating slots, as shown and described.

DESCRIPTION

FIG. 1 is a front perspective view of the low-profile aquarium light with ventilating slots, showing the top surface of the light. The dashed lines illustrate unclaimed structure.

FIG. 2 is a rear perspective view thereof, also showing the top surface of the light. The dashed lines illustrate unclaimed structure.

FIG. 3 is a rear perspective view thereof, showing the bottom surface of the light. The dashed lines illustrate unclaimed structure.

FIG. 4 is a front perspective view thereof, also showing the bottom surface of the light. The dashed lines illustrate unclaimed structure.

FIG. 5 is a top view thereof. The dashed lines illustrate unclaimed structure.

FIG. 6 is a front view thereof.

FIG. 7 is a rear view thereof. The dashed circle on the left side of the figure illustrates unclaimed structure.

FIG. 8 is a bottom view thereof. The dashed lines illustrate unclaimed structure; and,

FIGS. 9 and 10 are side views thereof. The dashed lines in both figures illustrate unclaimed structure.

The broken or dashed lines in FIGS. 1-5 and FIGS. 7-10 illustrate unclaimed structure. For information purposes, the first unclaimed structure, as shown in FIGS. 1-5 and FIGS. 7-8, represents the strain-relief boot of the power cord for the light, which is attached to the rear surface of the light. (Note that in FIG. 7, this unclaimed structure is represented by a simple dashed circle.) Also, FIGS. 1-4 and FIGS. 9-10 show additional unclaimed structure on the sides or ends of the light, representing mounting holes for a pair of mounting brackets (the brackets themselves are not shown). This unclaimed structure is shown most clearly in the side views of the light, FIGS. 9 and 10.

1 Claim, 7 Drawing Sheets
